UNITED STATES PATENT OFFICE

2,467,323

FREIGHT HANDLING

Waldo W. Longwell, Elmira, N. Y.

Application July 25, 1944, Serial No. 546,495

4 Claims. (Cl. 104—91)

1

This invention relates to freight handling and has special reference to a load transferring device. More particularly the invention relates to a device for loading railroad cars, trucks and the like and for unloading the same.

One important object of the invention is to provide a load transferring device having a novel means for adjustment to height to suit the vehicle into which or from which the load is to be moved.

A second important object of the invention is to provide a device of this description wherein the parts to be adjusted for height will be of relatively light weight.

Heretofore it has been common to provide load transferring devices wherein a beam is supported from a frame resting on a loading platform or the like and wherein the legs of the frame are adjustable for height. Such a device requires the movement of the entire upper part of the frame in making the adjustment and consequently this requires considerable power.

A third important object of the invention is to provide a load transferring device wherein only the usual rail or track and the hoist itself will be required to be raised or lowered.

The fourth important object of the invention is to provide a device of this kind having an extensible arrangement whereby the load may be carried between the top of the box car or truck, this extensible arrangement being suitable means for adjustment at its free end.

With the above and other objects in view, as will be hereinafter apparent, the invention consists in general of certain novel details of construction and combinations of parts presently to be fully described, and which are illustrated in the accompanying drawings and particularly claimed.

In the accompanying drawings:

Figure 1 is a side elevation of the complete device showing its relation to a loading platform and a box car.

Figure 2 is a section on line 2—2 of Figure 1 to an enlarged scale.

Figure 3 is a section on line 3—3 of Figure 2.

Figure 4 is an enlarged section on line 4—4 of Figure 1.

Figure 5 is a fragmentary section to enlarged scale on line 5—5 of Figure 1.

Figure 6 is an enlarged side elevation of the free end of the extension rail used herein together with its support.

Figure 7 is a fragmentary section on line 7—7 of Figure 6.

Figure 8 is a detail section showing the coupling

2

for holding the main rail and the extension rail together.

Figure 9 is an enlarged detail section on line 9—9 of Figure 1.

- 5 In the embodiment of the invention as herein illustrated there has been shown a loading platform 10 whereon is erected a building structure including an overhead frame provided with longitudinal beams 11 and spaced transverse beams 12. 10 Depending from the transverse beams 12 are stirrups 13 longitudinally spaced along the beams 12 and carrying at their lower ends longitudinal beams 14. Also depending from the longitudinal beams 11 are spaced sets of four guide bars 15, 15 the beams 14 lying between pairs of these guide bars. Extending transversely of the structure is a pair of transverse beams 16. The ends of these beams extend between the guide bars 15 of the several pairs at each end of the said structure. 20 Interposed between the beams 14 and the ends of the beams 16 are suitable blockings 17 and it will be obvious that by selecting the proper number and size of these blockings the beams 16 may be held at any desired height within the scope of the 25 structure above the beams 14.

Bolted centrally to the underside of the beams 16 is a rail or track 18 whereon runs a trolley 19 supporting any suitable form of hoist as at 20. It is possible, by adjustment of the blockings 17, to 30 position the track or rail 18 to any desired height above the platform 10 and it will be noted that in making this adjustment all that has to be supported for raising or lowering is the pair of beams 16, the track or rail 18, the trolley 19 and the hoist 20.

The platform 10 may be provided with any desired form of conveyor 21 whereby a load L may be brought into position below the hoist and transferred to the structure above described, this 40 load being arranged for connection to the hoist by suitable means such as the sling S.

Extending outwardly of the above described structure is an extension track or rail 22 which aligns with the rail 18. To the outer end of the 45 rail 18 and to the inner end of the rail 22 are secured a pair of angles 23 which can be bolted together as at 24 to hold the rail sections 18 and 22 securely connected. As a means for supporting the outer end or free end of the extension 50 rail 22 there is employed a post comprising a lower tubular section 25 wherein telescopes an upper tubular section 26 provided with vertically spaced holes or openings 27 for the reception of the bolt 28 which rests upon the top of the lower 55 section 25 and thus prevents retraction of the

telescopic upper section 26. This upper section carries a shoe 29 wherein fits the lower flange portion of the end of the extension rail 22, slipping of one part on the other being prevented by means of the set screw 30.

Here again it will be noted that in adjusting for height the only parts to be supported will be the relatively light section 22 and upper tubular section 26.

It will be noted that no heavy adjustment frame is required for the rails such as would be the case did such frame have legs resting on the platform 10 and arranged for vertical lengthening or shortening.

While there is herein shown and described the preferred embodiment of the invention, it is nevertheless to be understood that minor changes may be made therein without departing from the spirit and scope of the invention as claimed.

I claim:

1. In load transferring apparatus, an overhead frame, hangers depending from said frame, laterally spaced longitudinal beams carried by said hangers, transverse beams spanning the space between said longitudinal beams, a longitudinal rail carried by said transverse beams below the same, and means to effect desired spacing of the transverse beams above the longitudinal beams.

2. In load transferring apparatus, an overhead frame, hangers depending from said frame, laterally spaced longitudinal beams carried by said hangers, transverse beams spanning the space between said longitudinal beams, a longitudinal rail carried by said transverse beams below the same, and blocking removably inserted between the longitudinal beams and the ends of the transverse beams.

3. In load transferring apparatus, an overhead frame, hangers depending from said frame, laterally spaced longitudinal beams carried by said

hangers, transverse beams spanning the space between said longitudinal beams, a longitudinal rail carried by said transverse beams below the same, means to effect desired spacing of the transverse beams above the longitudinal beams, and guide bars depending from said overhead frame and guiding the ends of said transverse beams.

4. In load transferring apparatus, an overhead frame, hangers depending from said frame, laterally spaced longitudinal beams carried by said hangers, transverse beams spanning the space between said longitudinal beams, a longitudinal rail carried by said transverse beams below the same, blockings removably inserted between the longitudinal beams and the ends of the transverse beams, and guide bars depending from said overhead frame and guiding the ends of said transverse beams.
